UNITED STATES PATENT OFFICE.

BENJAMIN F. FREEBLE, OF BROWNSVILLE, PENNSYLVANIA.

RAILWAY-CAR.

No. 875,906.

Specification of Letters Patent.

Patented Jan. 7, 1908.

Application filed June 7, 1907. Serial No. 377,794.

To all whom it may concern:

Be it known that I, BENJAMIN F. FREEBLE, a citizen of the United States, residing at Brownsville, in the county of Fayette and 5 State of Pennsylvania, have invented certain new and useful Improvements in Railway-Cars, of which the following is a specification.

My invention relates to railway cars, which will be hereinafter more fully described, 10 illustrated in the drawings, and particularly pointed out in the claims.

The primary object of my invention is to provide a car which will insure comfort and safety to passengers against injury in all ordinary accidents. 15

Another object of my invention is to provide safety to livestock and other property while in transit in cars.

A further object of my invention is to 20 maintain a perfect equilibrium of the interior of the cars constructed in accordance with my invention under all conditions except the telescoping of the same, and this though the exterior of the car may turn over 25 and over.

These objects are attained in the structures of cars represented in the accompanying drawings forming a part of this application and in which—

30 Figure 1, is an elevation of a portion of my improved car partly in section showing the elevation of the circular tracks and also the construction at the doorway to allow for the swinging of the inner portion independently 35 of the vestibule. Fig. 2, is an end view of the car one-half being finished and the other half showing the metal end plates fastened to the respective hoops or tracks. Fig. 3, is a detail elevation of the hoops or tracks 40 showing the base beams and journals for the rollers, and also showing the method of attaching the outside metal plates of the car. Fig. 4, is a detail section on line 4—4 of Fig. 3, showing the construction of the floor supports and the roller journals. Fig. 5, is a detail section showing the arrangement of the 45 windows to allow for the swinging of one portion within the other. Fig. 6, is a detail section showing construction of sliding door 50 when the car is to be used as a livestock or freight car.

My invention relates only to the body of the car, which is preferably made of iron or steel, and has no relation to the car trucks, 55 springs and bolsters.

Referring now to the drawings, A represents a part of the car, Fig. 1, in ordinary construction, and B represents a sectional view as shown in said figure. C represents the hoops or bands and C' the tracks. These 60 hoops and tracks are placed about equi-distant of the length of the car, as shown in Fig. 1, having in the main portion of the car two windows between the tracks.

In Fig. 2 an end view of the car is shown, 65 a part of it being finished and a part unfinished, and showing the metal end plates F fastened to the hoops or bands.

In Fig. 3 the floor D of the interior chamber of the car is shown, and also the trucks 70 D' on the tracks, and rollers d between the track and the hoop or band, with the manner of fastening those trucks so as to roll freely and easily upon the tracks. In this figure the I-beams E are shown running longitudinally of the car. 75 The outer frame of the car is also shown in part and the location of the I-beams relative to such frame.

In Fig. 4, a detail section is shown of the truck riding on the hoop or band, as indicated 80 in line 4—4 of Fig. 3. This shows how the truck will freely pass over the interior surface of the hoop or band.

In Fig. 5 it is shown how the windows will be protected as the interior of the car moves 85 around. These windows, as will be seen in Fig. 1, are within the space occupied by two tracks and two bands and so are not affected by the moving of the interior portion of the car. 90

In Fig. 6 provision is made for a sliding door on the side of the car adapted for the transportation of livestock and of freight. This sliding door permits of the ingress and egress of livestock and of freight. The sliding 95 door, as will be understood, opens the space between what would in the ordinary car be given to two windows, or substantially such space. There is nothing essentially different in this door from that in the ordinary freight 100 cars. The interior of the car, however, is provided with the hoops and tracks and rollers so that the interior of the car will accommodate itself to the condition in which the car may be situated. In other words, the interior of the car in which the stock or freight stand or lie will turn so as to maintain the equilibrium of the interior of the car no matter what position the exterior of the car may be in. This equilibrium of the interior, will 105 110

be maintained at all times independently of the position of the exterior, through the supporting of the circular interior hoops or bands upon the outer circular tracks by means of the wheels or rollers and bearings (Figs. 3 and 5) attached to the I-beams which form the framework of the floor and upon the terminals of the interior bands, not only in case of the overturning of the car but at all times during the ordinary progress of the car, and will eliminate all rocking from side to side and jolting motions of the interior, on the roughest roadbeds or sharpest curves, whether compound or simple. It is further evident that this provision for the maintenance of an equilibrium of the interior at all times will, in case of overturning of the car, greatly lessen the number of that class of accidents occurring by reason of the throwing about promisingly of the occupants of such cars as do not provide for this maintenance of the equilibrium of their interior at all times.

It will also be observed that provision is made for the operation of the windows by having the window proper a part of the interior finish, just outside the sash, the frame on each side of the window is divided into two parts by an arc of a circle the center of whose radius is the common center from which all the circles are worked, which parts act independently of each other with a free yet concentric circular movement, the parts of the window inside of this arc being a part of the interior of the car and all that part of the frame outside of this arc being a part of the exterior body of the car.

In my car the steps and doors will be the same as in the ordinary cars.

Having thus described my invention, its use and operation, what I claim and desire to secure by Letters Patent is:—

1. In a railway car the combination with a

stationary frame of an interior rotary chamber, substantially as described.

2. In a railway car the combination with 45 its frame, of an interior revoluble chamber, and means for supporting and maintaining the same in position, substantially as described.

3. In a railway car the combination with 50 its frame provided with a series of circular tracks, of an interior, rotary chamber provided with trucks and rollers, substantially as described.

4. In a railway car the combination with 55 its exterior frame having interior circular tracks, of an interior rotary frame provided with tracks and rollers, and a stationary floor, substantially as described.

5. In a railway car the combination with 60 its body frame provided with windows and doors and having interior tracks, of an interior rotary frame having a floor supported by a hoop, trucks secured to the floor, and rollers between the hoops and tracks, substantially 65 as described.

6. In a railway car the combination with its body frame supported on trucks, of an interior rotary chamber, having seats for the accommodation and comfort of passengers, 70 substantially as described.

7. In a railway car the combination with its body frame resting upon and carried by trucks and provided with sliding doors, of an interior rotary chamber having a floor supported by a hoop, and trucks secured to the floor, substantially as described. 75

In testimony whereof I have signed my name to this specification in the presence of two subscribing witnesses.

BENJAMIN F. FREEBLE.
